UNITED STATES PATENT OFFICE.

BERNHARD WALCHNER, OF NEW YORK, N. Y.

MACHINE FOR SPLITTING MICA.

No. 901,130.

Specification of Letters Patent.

Patented Oct. 13, 1908.

Application filed February 21, 1908. Serial No. 417,056.

To all whom it may concern:

Be it known that I, BERNHARD WALCHNER, a citizen of the Empire of Germany, residing in New York, in the borough of Queens, 5 county of Queens, and State of New York, have invented certain new and useful Improvements in Machines for Splitting Mica, of which the following is a specification.

This invention relates to an improved machine for splitting mica blocks into thin sheets or laminæ of uniform thickness in a quick and reliable manner.

Mica sheets were heretofore cut by hand from blocks of mica. Various attempts have 15 been made for splitting mica-blocks into thin sheets or laminæ by machine but without giving satisfactory results.

The object of this invention is to furnish a machine by which blocks of mica are split 20 into sheets of uniform size similar to hand-cut sheets and by which the laminæ are conducted by an air-blast into a suitable receptacle; and for this purpose the invention consists of a machine for splitting mica 25 which comprises a horizontal table, means for imparting reciprocating motion to the same, a splitting knife located on said table, means for oscillating said splitting knife when the same arrives near the block of 30 mica, means for holding the block of mica in line with the axis of the knife, means for intermittently supplying an air-blast to the sheet split off from the block, and means for simultaneously releasing the block for permitting the sheet to be split and conducted 35 off by the action of the air-blast.

The invention consists further of certain details of construction and combinations of parts which will be fully described herein- 40 after and finally pointed out in the claims.

In the accompanying drawings, Figure 1 represents a side-elevation of my improved machine for splitting mica, Fig. 2 is a side-elevation of the operative parts of the machine showing the same in the act of splitting off a sheet of mica, Fig. 3 is a plan-view partly in horizontal section on line 3, 3, Fig. 1, and Fig. 4 is a plan-view of the splitting knife showing it in the act of splitting off a 50 sheet from the upper end of the block of mica.

Similar letters of reference indicate corresponding parts throughout the figures.

Referring to the drawings, *a* represents 55 upright standards, two of which are arranged at each end of the machine, said stand-

ards being made approximately U-shaped in cross-section and connected in lateral as well as longitudinal direction by suitable brace-pieces. The standards *a* serve for guiding horizontal cross-bars *b*¹, the ends of which are shaped to fit into the upright standards *a*, the cross-bars supporting a table *b* which extends from the pair of upright standards at one end of the machine to the pair of 65 standards at the opposite end of the same. To the horizontal cross-bars *b*¹ are swiveled the lower beveled ends of upright feed-screws *b*² which pass through the upper ends of the standards *a*, and which receive intermittent motion by means of intermediate gear-wheel transmissions from a vertical shaft *S* that is supported in neck-and-step bearings of transverse pieces *d*, *d*¹ which connect the supporting frame of the machine, 70 as shown in Fig. 1. The shaft *S* engages by a bevel gear-wheel *e* at its upper end two pairs of bevel gear-wheels *e*¹, which latter are located at the inner ends of four intermediate shafts *e*² which extend diagonally 75 from the bevel gear-wheel of the vertical shaft *S* towards the upper ends of the feed-screws *b*², and which carry at their outer ends bevel gear-wheels *e*³ which mesh with bevel gear-wheels *e*⁴ that are swiveled to the 80 upper ends of the upright standards *a*. The bevel gear-wheels *e*⁴ are provided with interiorly-threaded hubs which mesh with the threaded upper ends of the feed-screws. To the lower end of the upright shaft *S* is 85 applied at ratchet-wheel *r* which is engaged by a pawl *r*¹ that is located at the inner end of a horizontal, spring-actuated rod *r*² which is reciprocated in a stationary guide-sleeve *r*³, by a cam *r*⁴ on the driving shaft *S*¹, acting on an anti-friction roller *r*⁵ of the rod *r*², so as to move at each rotation of the shaft *S*¹ the ratchet-wheel for the distance of one tooth and turn thereby the vertical shaft *S* on its axis, and by the intermediate transmitting mechanism described, the feed-screws *b*² so that the cross-bars *b*¹ and the table *b* are fed intermittently in downward direction for the thickness of the sheet or lamina of mica to be split off with each rotation of the shaft *S*¹.

One the table *b* are arranged a plurality of splitting knives *k*, according to the length of the machine and the number of mica-blocks to be simultaneously acted upon. 110 The rear-ends of the shanks *k*¹ of the knives *k* are pivotally connected with a longitudi-

nal bar k^2 . The shanks of the knives are fulcrumed to the table b , while the sharp front-ends or edges of the knives are made with a curve inclined towards the longitudinal axes of the knives so as to be moved quickly through the ends of the blocks when the table is moved forward and brings the edges of the knives towards the blocks of mica. The longitudinal bar k^2 receives laterally reciprocating motion during the forward and backward motion of the table by means of a roller k^3 at one end of the same, which roller moves along an inclined cam k^4 on one of the cross-bars b^1 so as to impart by the laterally-reciprocating motion of the bar k^2 a quick oscillating motion simultaneously to all the splitting knives. The table b receives reciprocating motion from the driving shaft S^1 by means of an eccentric e^x and a connecting rod f strapped thereto, the opposite end of the connecting-rod being pivoted to the rear-end of the table b . The driving shaft S^1 receives rotary motion from an electric motor or other power-transmission. The reciprocating motion of the table in connection with the oscillating motion of the splitting knives produces at each forward motion of the table the splitting off of the uppermost layers or laminae of the mica-blocks m which are supported on brackets g attached to the supporting frame of the machine. The blocks of mica are first trimmed to the proper shape and then placed in position on the brackets g and held thereon by followers g^1 each of which is provided with a stem g^2 guided in a cylindrical casing g^3 that is attached by brackets to the supporting frame of the machine, said stem being acted upon by a helical spring g^4 which is interposed between an interior shoulder g^5 in the upper portion of the casing and a transverse pin g^6 on the stem g^2 , as shown in Fig. 1. Above each follower g^1 are arranged at each side of its stem g^2 antifriction-rollers g^7 which are engaged by the forked end of a lever h which is fulcrumed to ears of an upright standard h^1 that is attached to the table b , and which can be adjusted to different inclinations by means of a thumb-screw h^2 which passes through a lug h^3 at the rear-end of the forked lever and engages a lug h^4 on the upper rear-part of the standard h^1 . During the forward motion of the table, the inclined lever h moves forward with it, and engages by its forked end the antifriction-rollers at both sides of the stem g^2 so as to lift the follower g^1 away from its block of mica at the moment when each knife is quickly passing across the inner edge of the upper portion of the block of mica, as shown in Figs. 2, and 4.

Immediately above each splitting knife k is arranged the nozzle n^1 of an inclined air-supply pipe n , which is supported on the

table b and reciprocated therewith. In the upper part of the air supply-pipe n is arranged a stopcock n^2 which is opened or closed by a crank-arm n^3 , the upper end of which is connected by a pivot-rod n^4 with a stationary ear n^5 on the supporting frame of the machine, as shown in Fig. 1, said stopcock being connected by a flexible hose n^6 with a blower or other source of supply of air under pressure. At each forward motion of the table b and simultaneously with the splitting of the upper edge of the block of mica by the oscillating knife, the air-supply pipe is opened so that a blast of air is passed under the sheet as the sheet is split off at its inner edge by the knife, whereby the remaining portion of the sheet or lamina is lifted off separated bodily from the block and then blown off by the air-blast and delivered into a suitable receptacle (not shown) near the mica-block simultaneously with the release of the follower from the same. The block of mica is held in position on the bracket g against the action of the splitting knife by a clamping plate p which is applied to the block in connection with a clamping lever p^1 so as to be prevented from shifting on the bracket, as shown in Figs. 1 and 3.

The machine can be arranged with one splitting knife or with a plurality of splitting knives each of which is operated in connection with an individual air-supply and forked lever for lifting the follower of the mica-block and permit the splitting off and lifting of a plurality of sheets from a corresponding number of mica-blocks and then blowing them away from the remaining portions of the blocks.

During the return of the table b the stopcock of the air-supply-pipe is automatically closed and the air-blast interrupted, as shown in Fig. 1; Fig. 2 showing the open position, ready for splitting off and blowing away a sheet of mica. At each rotation of the driving shaft S a forward and backward motion is imparted to the table on which the splitting knives, air-nozzles and forked levers for lifting the followers are supported. Simultaneously with the forward and backward motion of the table, the pawl and ratchet-mechanism is operated by which the motion-transmitting mechanism of the feed-screws and the lowering of the table for the thickness of one sheet, so that a large number of sheets of mica can be separated from their blocks in a given time in a regular and effective manner.

Having thus described my invention, I claim as new and desire to secure by Letters Patent:

1. In a machine for splitting mica, the combination of a reciprocating table, a splitting knife fulcrumed to said table, means for imparting laterally oscillating motion to said

splitting knife, means for supporting a mica-block adjacent to the feed-table, means for clamping said block in position, means for supplying a blast of air under the layer or 5 lamina of mica split off by the knife, and means for releasing the clamping device simultaneously with the splitting action of the knife.

2. In a machine for splitting mica, the 10 combination of a reciprocating feed-table, a splitting knife fulcrumed to said table, means for oscillating said splitting knife at the end of the forward motion of the table, a nozzle adjacent to the knife, means for 15 supplying a current of air under pressure through the nozzle during the oscillation of the knife, means for supporting a block of mica in line with the splitting knife, and means for lowering the feed-table after each 20 actuation of the knife and air-blast.

3. In a machine for splitting mica, the combination of a horizontally-reciprocating feed-table, a splitting knife fulcrumed to the same, means for oscillating said knife at the 25 end of the forward movement of the feed-table, a nozzle located adjacent to the edge of said knife, means for supplying a current of air under pressure to said nozzle simultaneously with the splitting action of the 30 knife, means for supporting a block of mica in line with said knife, a spring-actuated follower for holding said block of mica in position, and a spring-actuated lever adapted to engage the stem of the follower for moving it away from the mica block simultaneously 35 with the splitting action of the knife and the action of the air-blast so as to permit the blowing off of the layer or lamina split off from the block of mica.

4. In a machine for splitting mica, the 40 combination of a horizontal feed-table, means for reciprocating the same, a splitting knife fulcrumed to said table, means for imparting oscillation motion to said splitting knife 45 when the same arrives at the end of its forward motion, an air-supply nozzle located adjacent to the edge of the knife, means for

supplying a current of air under pressure to said nozzle during the splitting action of the knife, means for supporting a block of 50 mica in line with the splitting knife, a spring-actuated follower for holding the block in position, means for releasing the follower from the mica block for permitting the blowing off of the sheet or lamina split 55 off after each actuation of the splitting knife and air-supply mechanism, and means for intermittently lowering the feed-table with the knife, nozzle and follower-releasing mechanism after a sheet or lamina of mica 60 has been split and blown off.

5. In a machine for splitting mica, the combination of a reciprocating feed-table, a splitting knife fulcrumed thereto, means for oscillating the splitting knife at the end of 65 each forward motion of the table, means for supporting a block of mica in line with the knife, a spring-actuated follower for holding the block of mica in position, and a forked lever engaging the stem of the follower for 70 releasing the block during the splitting action of the knife.

6. In a machine for splitting mica, the combination of a reciprocating feed-table, a splitting knife fulcrumed thereto, means for 75 oscillating the splitting knife at the end of the forward motion of the table, means for supporting a block of mica in line with the knife, a spring-actuated follower for holding the block, a forked lever adapted for releasing the follower from the block of mica, an air-supply nozzle, and means for supplying an air-blast through said nozzle simultaneously 80 with the splitting off of a sheet or lamina of mica for blowing it away from the 85 block.

In testimony, that I claim the foregoing as my invention, I have signed my name in presence of two subscribing witnesses.

BERNHARD WALCHNER.
